UNITED STATES PATENT OFFICE

FLOYD L. SCOTT, OF HOUSTON, TEXAS, ASSIGNOR TO HUGHES TOOL COMPANY, OF HOUSTON, TEXAS, A CORPORATION OF TEXAS

LUBRICATOR COUPLING

Application filed October 19, 1928. Serial No. 313,392.

My invention relates to couplings such as are employed in attaching a lubricator barrel to the head of a drill bit, adapted for use in deep well drilling. It is particularly designed for use with drills having a removable water course longitudinally of the head of the drill.

In well drilling it is necessary to provide a passage for flushing fluid downwardly through the drill-stem, and drill so that the cuttings from the drill may be washed away from the drill and be carried upwardly outside the drill stem to the surface. Powerful pumps are now employed for forcing the flushing fluid into the well for this purpose and as the flushing fluid contains mud and abrasive materials, it is found that the passages for the fluid through the head of the drill are subject to rapid wear. A removable and replaceable watercourse may therefore, be placed longitudinally of the head of the drill, so that when wear occurs, the watercourse may be removed and replaced by another one without the loss of the drill head.

This removable watercourse is shown in the patent to H. W. Fletcher, No. 1,482,787, granted February 5th, 1924. But, the removable water tube in the prior patent is threaded and screwed directly into the coupling member, the channels in the coupling being inclined downwardly to converge at the upper end of the tube and the threaded seat in which is secured. This structure has the objection that the flushing fluid is given a turbulence by the converging channels in the coupling, at the upper end of the tube and its seat, so that rapid wear occurs at the upper end of the tube. The material in the coupling to which the tube is secured, wears away rapidly so that the tube becomes loosened and develops leaks and the coupling or cage must be replaced nearly as often as the tube.

It is an object of my invention to so secure the flushing tube to the cage that the attaching connection will be protected from wear.

It is also desired to form the passage for the flushing fluid in the cage so that the flow may be open and the passage large to avoid wear at the upper end of the tube, and par-

ticularly at the point of attachment of the tube to the cage.

In the drawing, Fig. 1 is a central longitudinal section through a well drill, showing my invention employed thereon.

55

Fig. 2 is an enlarged detailed sectional view of the lubricator cage with the tube therein.

Fig. 1 shows a common type of well drill, having a head 1 with cutters 2 rotatable on the lower end thereof. The upper end of the head 1 has a threaded shank 3 for attachment to a drill stem or drill collar 4.

The lubricator barrel 5 is secured to the drill head by means of a coupling or cage 6 having an upper shank 6 engaging the barrel. The lower end of the cage is formed with a deep threaded recess 7 therein, the lower portion of which engages with a nipple 8 at the upper end of the drill head.

70

The lubricator cage serves to conduct lubricant from the barrel 5 to ducts 9 in the bit head, said ducts connecting with the passages 11 and 12 to direct the lubricant to the cutter bearings.

75

The cage also serves to direct the fluid from the interior of the drill stem, to the removable watercourse 13 in the head. Said watercourse is a tube of steel or other metal connected with the coupling or cage at its upper end and extending axially of the drill head to discharge water and flushing fluid to the lower end of the hole. The upper end of the tubes has a head 14 thereon which is secured by welding or otherwise rigidly to the tube. 80 This head 14 is threaded on its exterior to engage within the threaded recess 7 in the cage above the nipple 8 of the drill head. The tube extends through the head 14 thereon to project through the upper end of the recess 7 into a diametrical passage 15 in the cage. The upper end of the tube forms a tight fit with the cage above the recess 7 and its end is flush with the lower wall of the passage 15, which, as seen from Fig. 2, has a 85 flat lower side. I make the passage 15 comparatively large so that as free a flow as possible may be obtained for the flushing fluid.

90

95

It will be obvious that the threaded seat 7 100

and the shoulder 16 at the upper end of the head 14 of the tube make a fluid seal that cannot be easily worn. The flushing fluid entering the passage 15 will pass directly into 5 the upper end of the tube and such wear as occurs due to turbulence of the mud-laden liquid will take place at the extreme upper end of the tube, and in the passage 15 away from the threaded connection of the head 10 14. It will, therefore, take wear for a materially long period of time before the threaded connection between the tube and the cage will become materially worn so as to allow leakage or to loosen the tube. It is this at 15 tachment of the tube to the cage that forms the main object of the invention, and I have found that with this arrangement, the life of the cage is greatly increased.

What I claim as new is:

- 20 1. In a rotary drill bit, a drill head, a lubricator barrel, a tube for flushing liquid axially of said head, a coupling member connecting said lubricator barrel to said head, said coupling having a threaded recess in 25 its lower end to engage said head, and a head on said tube shaped to fit said recess above said drill head, an extending upper end on said tube projecting above the head thereon, said coupling having a diametrical passage 30 arranged at a right angle to the tube axis and communicating with the upper end of said tube.
2. In a rotary drill bit, a drill head, a lubricator barrel above said head, a removable flushing tube axially of said head, a coupling member connecting said lubricator barrel to said head, said coupling having a threaded recess in its lower end to engage said drill head, a diametrical fluid passage through 40 said coupling, said tube extending through said recess to connect with said passage, said passage having a flattened lower surface flush with the upper end of said tube, and means in said recess to engage said tube.
- 45 3. In combination, a lubricator cage for rotary well drills, said cage having a threaded nipple at its upper end for attachment to the lubricator barrel, and a threaded recess in its lower end for attachment to the 50 drill head, said cage having a diametrical passage above said recess, a tube extending through said recess and into said passage, and a head on said tube removably engaging said recess at a point spaced below said pas- 55 sage.

In testimony whereof I hereunto affix my signature this 9th day of October A. D. 1928.

FLOYD L. SCOTT.
